UNITED STATES PATENT OFFICE.

PERCY W. SHAW AND AUGUSTINE F. LITTLEFIELD, OF LYNN, MASSACHUSETTS,
ASSIGNORS, BY MESNE ASSIGNMENTS, TO UNITED SHOE MACHINERY COR-
PORATION, OF PATERSON, NEW JERSEY, A CORPORATION OF NEW JERSEY.

ART OF MAKING STIFFENERS FOR BOOTS AND SHOES.

1,256,937.

Specification of Letters Patent. Patented Feb. 19, 1918.

Application filed May 12, 1916. Serial No. 97,205.

To all whom it may concern:

Be it known that we, PERCY W. SHAW and AUGUSTINE F. LITTLEFIELD, citizens of the United States, residing at Lynn, in the county of Essex and State of Massachusetts, have invented certain Improvements in the Art of Making Stiffeners for Boots and Shoes, of which the following description, in connection with the accompanying drawings, is a specification, like reference characters on the drawings indicating like parts in the several figures.

This invention relates to a method of cutting material into articles the edges of which are beveled, and particularly to cutting from stock certain parts used in the manufacture of boots and shoes.

For convenience the description will be limited to a method of cutting counters from leather stock, but it should be understood that the invention may be employed in making similar articles, for example box toes, from any suitable material.

Hitherto it has been customary to die out counter blanks from a piece of leather and then to run the died out blanks through a skiving machine in order to give them a continuous beveled edge. There is a large amount of waste involved in carrying out this procedure; and to reduce this waste was one of the objects of the method of the patent to Engel No. 1,068,489 in which two series of counters were dipped out of a piece of leather, one series from the flesh side and the other series from the grain side. This method results in a large saving of stock, but has the disadvantage that half of the counters produced are "flesh counters". Such counters are not desirable to the trade and for various reasons do not find a ready sale.

The present invention aims to produce grain counters only and at the same time to effect a large saving of stock over the commonly used method in which the blanks are first died out and then skived. One feature of the invention comprises that improvement in the art of making stiffeners which consists in dipping out a stiffener from one side of a piece of stock and then dipping out a second stiffener from the same side in such manner that the distance between the two extreme edges of the cavities produced

by the removal of the stiffeners is less than the sum of the heights of the stiffeners.

Another feature of the invention relates to the article produced by the process which has been outlined above.

These and other features of the invention will be described in connection with an illustrative machine by which an exemplary method may be carried out and will be pointed out in the appended claims.

Referring now to the accompanying drawings,

Figure 1 is a rear elevation of an illustrative machine by which the method may be carried out;

Fig. 2 is a view partly in section of the rolls, knife and presser, the rolls being in angular position to permit a piece of stock to be removed from the machine;

Fig. 3 is an elevation showing the relative positions of the rolls and presser at the beginning of the feed movement;

Fig. 4 is a similar view after the rolls have advanced approximately ninety degrees from the position shown in Fig. 2;

Fig. 5 is a front elevation of the rolls and presser in the positions shown in Fig. 3;

Fig. 6 is a similar view with the parts in the position shown in Fig. 4. In Figs. 3, 4, 5 and 6 the first counter is being cut.

Fig. 7 is a view similar to Fig. 6 but showing the position of parts during the cutting of the second and subsequent counters, in which the presser holds up the beveled edge of the stock.

Fig. 8 is a plan showing how the counters lie in the stock;

Fig. 9 is a plan of the second and subsequent counters all of which have a small area of flesh on the grain side.

The frame 1 has two overhanging arms 3 and 5. In alined bearings in the upper arm and in the main part of the frame is mounted a shaft 7 to which is fast at one end a matrix roll 9 and near the other end two gears 11 and 13, the former gear meshing with a gear 15 on a suitable driving shaft having mounted thereon the usual fast and loose pulleys 17, 19. In bearings in the frame and in a yoke 21, the stem of which is yieldingly supported in a socket formed in the lower arm 5, is rotatably mounted a two-part shaft 23 having fast

to it a die roll 25. The parts of the shaft 23 are connected by an Oldham coupling 27 the inner portion of the shaft 23 having at its inner end a gear 29 which meshes with 5 the gear 13. An adjusting sleeve 31 threaded into the socket in the lower arm 5, and a stop nut 33 threaded on the reduced lower end of the stem of the yoke 21 furnish means for varying the tension of the spring 10 35 and for limiting the extent of upward movement of the yoke. A stationary knife 37 is held in adjusted position by a pinch bolt 39.

With this construction a portion of a piece 15 of stock presented to the rolls will be forced into the matrix in the upper roll, and as the stock is advanced a stiffener or other article having the shape of the matrix will be cut from the stock. The use of a die roll, a 20 matrix roll and a knife for producing articles of a desired shape is old, and the particular construction illustrated will not be described further except to state that the shape of the matrix illustrated is such that 25 a counter stiffener of the general outline shown in Figs. 8 and 9 having a thick middle portion and a continuous beveled edge is produced. Attention is directed, however, to the construction and arrangement of the 30 bearings of the rotary shafts which carry the rolls whereby a free and unobstructed space is provided which extends in all directions in a horizontal plane between the rolls. With this construction it is possible to operate 35 upon a piece of stock in a locality close to or remote from the margin thereof. This is a particularly desirable feature since it permits the operator to select the locality from which the counter is to be dipped out. 40 The present machine is adapted, among other uses, to cut counters from pieces of stock which have irregular outlines; and such pieces may be freely presented so as to form the counters by cuts extending in various directions with respect to any given 45 piece.

Ordinarily a series of counters are cut from a selected locality, as illustrated in Fig. 8, in which the first counter produced 50 is the one at the extreme left, the second, the next at the right, and so on. To accomplish this, the piece of leather 100 is fed between the rolls in the direction indicated by the arrow once for each counter produced. The counters are thus cut one at a time, and the base of each counter, as it lies 55 in the stock, underlies the top of the next preceding one except, of course, that of the first counter. The result is that a series of 60 counters are dipped out of the same side—that is the grain side—of the stock, of which the first is a perfect grain counter while those which follow each have a small portion of flesh surface caused by the overlap

which has been referred to above. This 65 flesh surface, however, extends along the base of the counter and produces no undesirable effect since the lower margin of the counter, in which this flesh surface occurs, is molded in or lasted in to form a flange 70 before it becomes part of a finished shoe. Fig. 9 is a plan of one of these counters in which the overlap is indicated at 200.

After the first counter has been dipped out a beveled edge is produced around the 75 hole indicated by the dotted line 41 which extends upwardly to the edge 43 of the cavity from which the counter has been removed. It will be seen that a part of the right-hand portion of this beveled edge is 80 to form a part of the second counter. If, however, after the removal of the first counter, the piece of leather were fed through the rolls without further mechanism than has been described, a part of this beveled 85 portion would hang down in the path of the knife and be cut off. By referring to Fig. 6, which illustrates the cutting out of the first counter and in which the line of cut is indicated at 45, it will be seen that 90 the right-hand edge of the leather is of uniform thickness and that consequently the upper or grain side of that portion of the leather which is to be cut out to form a counter is forced firmly up against the bottom of the matrix in the upper roll at that point as well as at all other points. Referring now to Fig. 7, in which the cutting out of the second counter is shown, the right-hand edge of the leather is no longer 95 of uniform thickness with the rest but is beveled or tapered and consequently would hang down more or less out of contact with the bottom of the matrix in the upper roll unless provision were made for supporting 100 it and pressing it into the matrix. 105

To provide for both of the conditions illustrated in Figs. 6 and 7 a groove 47 is cut in the lower roll 25 having at its bottom a cam 49. For approximately two hundred 110 and sixty degrees this cam is concentric with the roll and is so located as to hold a presser 51 in the position shown in Fig. 7 with the upper edge of said presser protruding from said slot. The presser, however, is recessed 115 at 53 to form two resilient fingers which may be moved toward each other by pressure. Normally, when no stock is between the rolls the presser projects, as has been explained. When the stock is first fed to the 120 rolls the presser is depressed to inoperative position as shown in Fig. 6, but thereafter, during the cutting out of the remaining counters of the series, it supports the beveled edge of the stock as illustrated in Fig. 7. As 125 best shown in Fig. 2, the rolls 9 and 25 have cut away portions which register once in every revolution.

In the operation the machine is brought to rest with the rolls in the position shown in Fig. 2 in which a piece of stock may be placed between the rolls and moved about as desired in order to permit the operator to select the locality from which the first counter is to be dipped out. After the cutting out of the first counter the stock is pulled back and moved sidewise, or in the direction of the height of the counter, a proper distance, and then the second counter is cut out. The counters are thus cut out from the grain side of the stock one at a time, in the direction of their length in such a manner that as they lie in the stock, they overlap as shown in Fig. 8. After a series of counters has been cut out, the stock may be moved in any desired direction to present a new locality to the rolls and knife.

Having thus described our invention, what we claim as new and desire to secure by Letters Patent of the United States is:

- That improvement in the art of making stiffeners which consists in dipping out a stiffener from one side of a piece of stock and then dipping out from the same side a second stiffener in such manner that the distance between the two extreme edges of the cavities produced by the removal of the stiffeners is less than the sum of the heights of the stiffeners.
- That improvement in the art of making stiffeners which consists in dipping out from one side of a piece of stock a series of stiffeners in such manner that as they lie in

the stock the top of each stiffener overlies the bottom of the next succeeding stiffener.

3. That improvement in the art of making stiffeners which consists in dipping out from one side of a piece of stock a series of stiffeners in such manner that the distance between the opposite edges of the first and last cavities produced by the removal of the stiffeners is less than the sum of the heights of all the stiffeners. 45

4. That improvement in the art of making stiffeners which consists in dipping out a stiffener from the grain side of a piece of leather and then dipping out from the same side a second stiffener in such manner that 50 the distance between the two extreme edges of the cavities produced by the removal of the stiffeners is less than the sum of the height of the stiffeners.

5. That improvement in the art of making stiffeners which consists in dipping out from the grain side of a piece of leather a series of stiffeners in such manner that as they lie in the stock the top of each stiffener overlies the bottom of the succeeding stiffener. 60

6. A stiffener having a substantially straight bottom and a curved top, there being a bevel on one side extending around the curved top and a bevel on the other side extending along the straight bottom. 65

In testimony whereof we have signed our names to this specification.

PERCY W. SHAW.

AUGUSTINE F. LITTLEFIELD.
